UNITED STATES PATENT OFFICE.

MAX JACOBSON, OF NEW YORK, N. Y.

DESIGN FOR AN ASTRAL BOARD.

59,657.

Specification for Design.

Patented Nov. 15, 1921.

Application filed June 19, 1920. Serial No. 390,259. Term of patent 3½ years.

To all whom it may concern:

Be it known that I, MAX JACOBSON, a citizen of the United States, and a resident of the city of New York, in the county of New York and State of New York, have invented a new, original, and ornamental Design for Astral Boards, of which the following is a specification, reference being had to the accompanying drawing.

The figure is a plan view of an astral or talking board, showing my new design.

I claim:

The ornamental design for an astral board, as shown.

Signed at New York, in the county of New York, and State of New York, this 17th day of June, A. D. 1920.

MAX JACOBSON.
